(57) **CLAIM**

The ornamental design for a speaker box as shown and described.

DESCRIPTION

FIG. 1 is a front elevation view of a speaker box showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof, and

FIG. 7 is a top-left perspective view thereof; and,

FIG. 8 is a back, left-side and top perspective view thereof.

The broken lines in the figures illustrate the portions of the speaker box that form no part of the claimed design.
